Bath Tubs,

Jordan & Holt Ballina, N.Y. Design. Patented Aug. 18th 1846.

Des. 78

Jordan L. Mott, New York City,
Letters Patent (Design No. 78) dated 18 August 1846

The schedule referred to in these Letters Patent and making
part of the same

To all whom it may concern

Be it known that

I, Jordan L. Mott of the City of New York in the State of New York have
made certain new and useful improvements in the shape or configuration of
a cast iron Bathing Tub; and I do hereby declare that the following is a
full and exact description thereof:-

The Bathing Tub which I am about to describe, is in
its lower part, similar in form to that for the shape or configuration of which,
I obtained Letters Patent of the United States under the provisions of the Act
of Congress of August 1842, but in my improved form I make this bottom
narrowed in proportion to the size of the tub, than I did in the one patented
as above. The upper edge of my improved tub has its sides and
ends straight, meeting each other at right angles excepting that there is
a slight rounding off of the actual angles for the better delivery of the
pattern in the act of casting. To produce the straight sides at the upper part
of the tub the slopes and curvatures of the respective sides are so modi-
fied, as to terminate in the rectilinear form of the upper part of the tub

as represented by the respective figures in the accompanying drawings, in which I have not only shown the tub, but likewise a casing of wood which is intended to surround it.

Fig. 1 is a top view of the tub; fig. 2 a vertical section of it from end to end through its middle; fig. 3 a vertical section of it in the line x...x, and fig. 4, a similar section in the line o...o of fig. 1. It is represented as having a flanch or projecting rim a. a. cast on its upper edge by which it is sustained on the wood work of casing b. b. in which it may be enclosed; said wood work may be formed into panals or otherwise ornamented as may be preferred, this being independent of the shape or configuration of the tub. Although I do not claim in the application any mechanical device which would constitute the subject matter of a patent under the general law for the promotion of the useful arts, I deem it proper to state that the shape or configuration of my tub is such as to ~~make~~ render it an article of special utility. By increasing the area of its upper portion, and narrowing its lower part, the quantity of water required for bathing, is less than when the bottom is relatively wider, and a more ample space is left for the spreading out of the water when a person is immersed in it, and the water, from such widening out, rises to a less height in consequence of such immersion. The inconvenience frequently experienced in common bathing tubs from the want of a ready escape of the steam from about the head and face of the bather, is also to a great extent obviated.

These results I of course do not claim, but what I do claim as new and desire to secure by letter Patent is the special shape, or configuration of my cast iron Bathing Tub, as herein fully described and represented.
